(57) **CLAIM**

The ornamental design for a toothbrush, as shown and described.

DESCRIPTION

FIG. 1 shows a front view of my design for a toothbrush;
FIG. 2 shows a side view thereof;
FIG. 3 shows a back view thereof;
FIG. 4 shows a bottom view thereof; and,
FIG. 5 shows a top view thereof.

The dotted lines showing the bristles are for illustration only
and do not form a part of the invention.
